UNITED STATES PATENT OFFICE.

AUGUST E. BLUHM, OF ROCHESTER, NEW YORK.

COMBINED GARMENT HANGER AND STRETCHER.

1,105,019.

Specification of Letters Patent.

Patented July 28, 1914.

Application filed September 5, 1912. Serial No. 718,743.

To all whom it may concern:

Be it known that I, AUGUST E. BLUHM, a citizen of the United States, residing at Rochester, in the county of Monroe and 5 State of New York, have invented certain new and useful Improvements in Combined Garment Hangers and Stretchers, of which the following is a specification.

The object of this invention is to produce 10 a combined garment hanger and stretcher that can be folded to occupy a small space for the purpose of transportation, and that can be opened for the purpose of supporting a coat or trousers, or both, or a skirt and 15 coat. These and other objects of my invention will be illustrated in the drawings, described in the specification and pointed out in the claims at the end thereof.

In the accompanying drawings, Figure 1 20 is a perspective view of my improved garment hanger and stretcher, shown extended ready for use for hanging garments. Fig. 2 is a detail view of the hanger and stretcher partially folded up. Fig. 3 is a detail view 25 of the hanger and stretcher fully folded up. Fig. 4 is a detail view of the hook by which the hanger and stretcher may be suspended. Fig. 5 is a bottom plan view of the joint between the two halves of the hanger and 30 stretcher. Fig. 6 is a detail perspective view of one of the clamps.

In the accompanying drawings, like reference numerals refer to like parts.

In the drawings reference numeral 1 indicates the pintle upon which the two halves 35 or frames of the hanger are pivoted.

2 and 3 indicate the two frames of the hanger, and 4 the upright or support for the hanger. The various metal parts of the 40 hanger, except as hereinafter specified, are made preferably of wire bent and twisted to the desired shape. The frames 2 and 3 have the free ends thereof bent up into the form of eyes or loops so as to make engagement 45 with the pintle 1. The sides of these frames 2 and 3 diverge from each other as they extend away from the pintle, and terminate in the oval looped ends 5 and 6. The outer end of each of the frames 2 and 50 3 is inset as indicated at 7 and 8 for a purpose that will presently be explained. The upper end of the upright or support 4 is finished in the shape of a T 16, as is indicated in Fig. 4, the wire being bent over to the 55 right substantially at right angles to the stem, and then to the left, then back to the

stem again, the free end of the wire 11 being slightly bent out so as to inclose therebetween and the T-shaped head of the support 4, the swivel 9 formed on the hook 10. 60 The T-shaped head of the upright 4 is made substantially as broad as the web 12 that will be hereinafter described.

The hook 10 is formed of a single piece of wire, the eye or swivel 9 being formed 65 thereon by twisting the wire into suitable shape. This swivel is formed independently of the upright 4 and is placed thereon before the T-shaped head is finished thereon. The T-shaped head is then finished leaving 70 the end 11 sprung slightly outward. The end 11 is then compressed against the upright 4 and the swivel is moved up over it to place, the spring in the end 11 being sufficient to hold the swivel firmly in place and 75 still permit its being moved down on the upright when desired. The swivel connection between the hook 10 and the upright 4 permits the hook to turn more than a quarter of a revolution on the upright, making 80 the parts correspondingly flexible of adjustment.

Connected to the outer ends of the frames 2 and 3 is the web 12, which web is looped 85 around the inset portions of the ends of the frames of the hanger, the inset portion thereof being wide enough to embrace the web so as to prevent it moving sidewise around on the frame. By this means the web is held securely in place at each end. The loop at 90 each end of the web is secured by the eyelets 13, 13. In the middle of the web a reinforcing piece 14 is provided, through which and through the web is placed the eyelet 15. The hook 10 can be inserted through this 95 eyelet so that the web can be placed in position below the hook, resting upon the T-shaped head 16 of the upright 4 by which the web is supported and held in place.

As shown in Fig. 1, when the parts are in 100 position, the two frames 2 and 3 are substantially in line with each other, forming one continuous frame, while the web makes therewith the two sides of an isosceles triangle, the hook 10 being at the apex thereof. 105

Upon the frames 2 and 3 I mount the spring clamps 17 and 18. These clamps are swiveled upon the wire of the frame upon which they are adapted to slide, the wire of the frame serving as the pivot for the two 110 halves of the clamps. Each of the clamps is provided with a suitable spring between

the jaws thereof, by which the jaws are yieldingly held together at their lower ends, as shown in Fig. 6.

Mounted upon the frame between the 5 clamps and the pintle are the helical springs 19 and 20, which springs normally expand to hold the clamps in the position shown in Fig. 1, with the clamps held firmly against the shoulders formed by the oval ends 5 and 10 6. The springs are capable of yielding sufficiently to permit of the movement of the clamps along the frame to the extent of several inches, so that garments of different sizes may be fastened between the clamps 15 and held in position thereby. Ferrules or sleeves 21 and 22 are also provided on the frames for holding the ends of the springs away from the joint. The frames 2 and 3 spread sufficiently to permit the clamps 17 20 and 18 to revolve at the outer end thereof, permitting the frames to fold up more compactly, as shown in Fig. 3.

The frames taper from the outer end toward the pivot and are of sufficient width to 25 firmly hold between them the web when the frame is folded up.

Having thus described my invention, what I claim as new and patentable is as follows:

1. A folding wire garment hanger and 30 stretcher, comprising a pintle having two frames pivotally mounted thereon, and an upright support pivotally mounted on said pintle between said frames, each of said frames terminating in an oval-shaped enlargement extending transversely thereto, said enlargements forming shoulders with the inner portion of the frame, a clamp 35 mounted to slide on each of said frames, and a spring interposed between said clamp

and said pintle and adapted to exert a constant outward tension on the clamp and to hold said clamp normally against one of the shoulders of the frame. 40

2. A folding wire garment hanger and 45 stretcher, comprising a pintle having two frames pivotally mounted thereon, and an upright support pivotally mounted on said pintle between said frames, each of said frames terminating in an oval-shaped enlargement extending transversely thereto, 50 said enlargements forming shoulders with the inner portion of the frame, a clamp mounted to slide on each of said frames, a spring interposed between said clamp and said pintle and adapted to exert a constant 55 outward tension on the clamp and to hold said clamp normally against one of the shoulders, and a ferrule interposed between the inner end of the spring and said pintle.

3. A folding wire garment hanger and 60 stretcher, comprising a pintle and two frames pivotally mounted thereon, each of said frames terminating in an enlarged outer portion forming an abrupt shoulder at the junction of said portion with the main part 65 of the frame, a clamp slidably mounted on the frame, and a spring on the frame acting with a constant expansive tendency upon the clamp and adapted to hold said clamp against said shoulder, said spring being 70 yieldable to allow the clamp to be moved to different points on the frame.

In testimony whereof I affix my signature in presence of two witnesses.

AUGUST E. BLUHM.

Witnesses:

LENA M. ASH,
ALICE M. JOHANNS.
